UNITED STATES PATENT OFFICE.

WILBUR S. SHEPPARD, OF COLORADO SPRINGS, COLORADO.

ELECTRICAL HEATER.

1,099,999.

Specification of Letters Patent.

Patented June 16, 1914.

Application filed July 25, 1913. Serial No. 781,173.

To all whom it may concern:

Be it known that I, WILBUR S. SHEPPARD, a citizen of the United States, residing at Colorado Springs, in the county of El Paso 5 and State of Colorado, have invented certain new and useful Improvements in Electrical Heaters, of which the following is a specification.

This invention relates to improvements in 10 electrical heaters and particularly to such as are adapted especially for use in motor vehicles.

The object in view is the production of a 15 simple and compact structure occupying a minimum amount of space while capable of radiating a maximum number of heat units.

A further object in view is the provision 20 of an electrical heater of the type indicated having readily accessible parts and susceptible of assemblage and dismantling with ease and facility.

With these and other objects in view the invention comprises an external casing, an internal frame, the casing being formed with 25 an opening of sufficient dimensions for enabling the introduction and removal of the frame, a detachably mounted closure for the opening, and electrical heating means sustained by the frame.

30 The invention also comprises certain other novel constructions, combinations, and arrangements of parts as will be hereinafter specified and claimed.

In the accompanying drawings: Figure 1 35 is a perspective view of a heater embodying the features of the present invention. Fig. 2 is a longitudinal vertical central section taken therethrough, parts being seen in elevation. Fig. 3 is a transverse vertical section therethrough.

40 Referring to the drawings by numerals, 1 indicates the casing of a housing which in the preferred embodiment as illustrated in the accompanying drawings consists of a 45 rectangular tubular casing having open ends. The casing 1 preferably consists of sheet metal and for facility of distribution of heat units may be provided with apertures 2, 2, the casing being lined internally 50 with wire gauze or mesh 3. The gauze is preferably held in place by bolts or other suitable attaching means 4 distributed appropriately about the casing 1.

55 Arranged within the casing 1 is a heater frame 5 the frame being rectangular in form. Each of the end members of the

frame 5 is formed with a series of apertures 5' through which extend the tubes 6, each of the tubes being secured in place in any preferred manner as by having its end portion split or cut into a series of tabs and the latter being bent to a radial position as indicated by 7. Surrounding each tube 6 is a wrapping of asbestos 8. As many of the tubes 6 may be provided as desired but for 60 a heater of average size I prefer to employ three, and each is provided with a resistance 9. This resistance 9 preferably consists of a winding of German silver wire or other resistant conductor wound above the outside 70 of the asbestos wrapping 8 of the respective tubes 6. Spaced binding posts 10 and an intermediate binding post 11 are sustained by one end of the frame 5, each of said binding posts engaging an insulating plate, as 75 for instance, a mica sheet 12. The shank of each binding post 10 and 11 extends through the respective end portion of the frame 5 being surrounded by insulating sleeve 13 which extends through the respective end of 80 frame 5 for obviating the danger of short circuiting. The inner ends of the resistance coils of the upper and lower tubes 6 are connected by a conductor 14 which is preferably protected by a noninflammable insulation 15, as for instance, a tube of pipe 85 clay. The outer end of the lowermost resistance winding is connected to the lower binding post 10, the corresponding end of the uppermost resistance winding being 90 similarly connected to the upper binding post 10. The outer end of the intermediate winding is connected to the upper binding post 10 and the inner end is connected by conductor 16 with the intermediate binding 95 post 11, the conductor 16 being insulated by the pipe clay tube.

In practice the three binding posts are employed to enable the extension of line wires therefrom to an appropriate switch, not 100 illustrated, for enabling the supplying of current to any two of the resistance windings at any time or when preferred, and for enabling a supply of current to all three windings at once. It is obvious, of course, 105 that since the windings are of high resistance material the passing of current therethrough will produce heat a comparatively large proportion of which will be radiated and some of which will be retained by the 110 asbestos which thus offers means for continuing somewhat the heat supply after the

2
current has been turned off. The ends of the tubes and adjacent parts have been referred to as inner and outer, reference being had to the binding posts as the place of the outer end, the opposite ends of the tubes being inner ends.

It is to be observed that the casing 1 is formed with open ends for facilitating the application and removal of the frame 5 and 10 to give the whole a proper finished appearance as well as to obviate unnecessary loss of heat units, said open ends being adapted to be closed by plates 17 of comparatively thick rigid material which plates are engaged by bolts 18, 18 the latter passing through portions of the casing 1 for clamping the casing about the end plates. One of the end plates 17 is fixed to one end of the frame 5 and the other end is spaced from the frame a sufficient distance for accommodating the binding posts 10 and 11. The outer face of each plate 17 is preferably lined with an asbestos sheet 19 and outside of the asbestos sheet is arranged a finishing plate 25 or sheet 20 for each end of the plate 17. The finishing sheet 20 is preferably the same form of material as that employed in the construction of the casing 1. The end plate 17 which is spaced from the frame 5 is 30 formed with an aperture 21 through which extend the wires from binding posts 10. It will thus become obvious that the structure, while particularly adapted for insuring compactness and efficiency in supplying 35 heat from a minimum amount of current consumption is also adapted for greatly facilitating accessibility to the parts as well as ease and facility of dismantling and assemblage.

40 To dismantle the structure when in the condition indicated in Fig. 1, it is only necessary to remove the several bolts 18, whereupon the end piece 17 adjacent the binding posts 10, 11 may be readily taken off, and 45 the frame 5 may be withdrawn by withdrawing the opposite end piece, which latter end piece is bolted or otherwise fixed to frame 5.

For avoiding any liability of short circuiting, the aperture 21 is preferably supplied with an insulator 22 through which a cord 23 for containing the three conductors from the respective binding posts extends. The lower end portion of each finishing 55 plate 20 depends below the casing 1 and is flared laterally and fixed at its lower edge in a block 24, thus forming supporting feet

for the heater, particularly employed to prevent scorching of the floor mat upon which it rests when in operation.

Having thus described my invention, what I claim as new is:

1. In a heater of the class described, the combination of a hollow casing open at its opposite ends, a frame arranged in said casing, heating means carried by said frame, a plate received in one end of the casing and removably connected with said frame, a second plate removably received in the opposite end of the casing, and in spaced relation with respect to said frame, finishing plates applied to the opposite ends of the casing and projecting below the latter to form feet for supporting the casing spaced from a floor or other base on which it is mounted, connections between said finishing plates and the removable plates received in the ends of the casing, and heater connections arranged in the space between the frame and the plate disposed in spaced relation to the latter.

2. In an electric heater, the combination with a casing having open ends, a frame movably mounted in the casing and adapted to be shifted through one of the ends thereof, a plate for closing the last-mentioned end of the casing, said plate being carried by the frame, a plate for closing the opposite end of the casing, the last named plate being spaced from the adjacent end of the frame, electric terminals carried by the last-named end of the frame between such end and the adjacent end plate, and electrical heating means sustained by the frame and connected to be supplied with current from said terminals.

3. In an electric heater, the combination of a heater frame, electrical heating means sustained thereby, a finishing casing surrounding the frame, the casing being formed with open ends and the frame being adapted to be moved through one of the ends, plates closing the ends of said casing, connecting means between one of said plates and the frame, finishing plates fixed to the last mentioned plates, and feet pendent from the finishing plates for sustaining the heater.

In testimony whereof I affix my signature in presence of two witnesses.

WILBUR S. SHEPPARD.
